[57] **CLAIM**

The ornamental design for a combined bowl and strainer therefor, as shown and described.

DESCRIPTION

FIG. 1 is a top, rear, right side perspective view of a combined bowl and strainer therefor showing my new design;

FIG. 2 is a bottom, front, right side perspective view thereof;

FIG. 3 is a right side elevational view thereof the opposite side being identical;

FIG. 4 is a top plan view thereof;

FIG. 5 is a bottom plan view thereof;

FIG. 6 is a front elevational view thereof;

FIG. 7 is a rear elevational view thereof;

FIG. 8 is a cross-sectional view thereof taken along line 8—8 of FIG. 4;

FIG. 9 is an enlarged fragmentary cross-section of FIG. 8;

FIG. 10 is a top, rear perspective view of the bowl portion shown separately for clarity of illustration;

FIG. 11 is a right side elevational view of the strainer portion shown separately for clarity of illustration;

FIG. 12 is a fragmentary top plan view of the strainer portion;

FIG. 13 is a fragmentary top perspective view of the strainer portion; and,

FIG. 14 is a fragmentary bottom view of the strainer portion.

FIG. 2.

FIG. 6.

FIG. 7.

FIG. 8

FIG. 9

FIG. 10.

FIG. 12.
